CONTROLLING PHASE RELATIONS BETWEEN STATIONS

Application filed October 19, 1927, Serial No. 227,303. Renewed September 13, 1929.

This invention relates to methods and arrangements for maintaining the current supplied from one station over a line to a distant station in a desired phase relation. More particularly, the invention has application to maintaining constant phase relations between the carrier waves of a plurality of broadcasting stations transmitting upon the same wave length.

10 When distant radio stations are connected by telephone lines so that they may broadcast the same program, it becomes desirable that all the stations use the same carrier frequency in order to reduce the number of wave lengths required for the one program. Such a method of operation, however, encounters the difficulty that slight changes in the relative phases of the radio frequency currents from the various broadcasting stations affect the field 15 strength in certain localities, thus causing received signals to vary in amplitude, and in some cases to vanish completely.

In accordance with the present invention, it is proposed to remedy this condition by 20 supplying a controlling current of some base frequency over wire lines to the various broadcasting stations, the common carrier wave at the various broadcasting stations being derived from or controlled by the base 25 frequency so transmitted. In order to compensate for the variation in phase produced upon the controlling or base frequency by reason of temperature or other variations of the line, a special automatic arrangement is 30 provided to produce in the line changes to compensate for the changes in phase.

Specifically, the present invention contemplates controlling the phase variation by transmitting the control current from the 35 originating station over a line to a distant station at which the phase variation becomes effective, and thence back over a similar line to the original station. A certain normal difference in phase may then be noted between the current leaving the original station and the current coming back. By observing variations in this phase difference and adjusting phase controlling networks in the outgoing and controlling line to compensate for the 40 observed variation, this current may be main-

tained at the distant station in a substantially constant phase relation with respect to the originating current source.

The invention may now be more fully understood from the following detailed description thereof when read in connection with the accompanying drawing, of which Figure 1 shows curves illustrating the principles underlying the invention; Figs. 2 and 3 illustrate schematically certain types of radio antennæ; Fig. 4 illustrates a circuit arrangement embodying one form of the invention; Fig. 5 is a diagram illustrating the operation of a push-pull detector forming the part of the mechanism illustrated in Fig. 4; and Fig. 6 shows with some degree of detail the controlling mechanism symbolically represented in Fig. 4.

As a simple illustration of varying field strength let us consider two broadcasting stations symbolically represented at the points designated East and West in Fig. 1. Each station may be supposed to have a similar antenna consisting of a vertical rod with equal sources of electromotive force between the rod and the ground. Under these circumstances, each antenna is surrounded by a magnetic field and an electric field, these fields decreasing in strength with increasing distance from the antenna. Only a few lines of force are shown in the diagram of Fig. 1 in order to indicate the direction of certain portions of the fields. The lines marked *e* and *e'* represent lines of force of the electric field, the arrows indicating the direction. Similarly, the circles marked *m* and *m'* indicate the lines of force of the magnetic field, entering and leaving the paper in a plane at right angles thereto. The circles with the crosses represent positive lines of force and the circles with the dots in the center represent negative lines of force.

If the current in each antenna is in phase, then at the point *a* midway between the stations the magnetic flux, *m*, surrounding the east antenna will be equal and opposite in direction to the magnetic flux, *m'*, surrounding the west antenna. The resultant magnetic field at point *a* is therefore equal to zero. However, if the phases of the generators

should differ by 180° , then at *a* the vectors representing the alternating magnetic fluxes would add, while at *b*, a point just one-quarter wave length distant from *a*, the fluxes would subtract. At *c* one-half wave length

to the magnetic field, while the second term is that due to the electric field.

The current flowing in the receiving antenna due to waves from the west station may be represented:

70

$$I_w = A_1 \cos \left(\omega t + \frac{2\pi x}{\lambda} + \psi_1 \right) + A_2 \cos \left(\omega t + \frac{2\pi x}{\lambda} + \psi_2 \right) \quad (2)$$

from *a*, the fluxes would again add. The same holds true approximately for locations within a short distance north or south of these points.

On the other hand, the individual electric fields *e* and *e'* are a maximum when the mag-

in which A_1 and A_2 are again magnitude constants, which may have the same or nearly the same values as in the case of equation (1), and ψ_1 and ψ_2 are phase angle constants.

These expressions may be rewritten in the form of resultant vectors, as follows:

75

80

$$I_E = \sqrt{A_1^2 + A_2^2 + 2A_1A_2 \cos(\theta_2 - \theta_1)} \cos \left(\omega t - \frac{2\pi x}{\lambda} + \theta_3 \right) \quad (3)$$

20

$$I_w = \sqrt{A_1^2 + A_2^2 + 2A_1A_2 \cos(\psi_2 - \psi_1)} \cos \left(\omega t + \frac{2\pi x}{\lambda} + \psi_3 \right) \quad (4) \quad 85$$

netic fields *m* and *m'* are a maximum. Due to their relative directions at point *a*, however, the resultant of *e* plus *e'* is a maximum while that of *m* plus *m'* is zero. As phase shifts occur, the location of maximum and minimum resultant electrostatic fields is changed.

It is, of course, possible to devise receiving 30 antennae structures which will respond to the magnetic fields without being substantially affected by the electric fields, and vice versa. For example, the loop type antenna such as is illustrated schematically in Fig. 2, 35 responds mainly to magnetic fields, while the antenna of the type conventionally indicated in Fig. 3 responds mainly to electric fields. The majority of antennae, however, such as L or T type antennae, are responsive to both 40 magnetic and electric fields.

With these considerations in mind, let us analyze the character of the current received where the antenna is responsive to both magnetic and electric fields and located at any 45 given point in the vicinity of *a* of Fig. 1. Assuming the point *a* lies midway between two similar transmitters, each transmitting through similar media, let *x* equal the distance from the point *a* to a receiving station 50 near *a* and located on the line *c*—*a* of Fig. 1. Also, let λ equal the wave length of both oscillators. Then the current flowing in the receiving antenna due to waves from the east 55 transmitter is:

$$I_E = A_1 \cos \left(\omega t - \frac{2\pi x}{\lambda} + \theta_1 \right) + A_2 \cos \left(\omega t - \frac{2\pi x}{\lambda} + \theta_2 \right) \quad (1)$$

60 In the foregoing equation, *t* is the time of transmission: ω is 2π times the frequency; A_1 and A_2 are magnitude constants; and θ_1 and θ_2 are phase angle constants. Also, the first term of the quantity represented by the right 65 hand side of the equation is the current due

In Equations (3) and (4), the symbols θ_3 and ψ_3 have the following values:

$$\theta_3 = \tan^{-1} \frac{A_1 \sin \theta_1 + A_2 \sin \theta_2}{A_1 \cos \theta_1 + A_2 \cos \theta_2} \quad (5) \quad 90$$

$$\psi_3 = \tan^{-1} \frac{A_1 \sin \psi_1 + A_2 \sin \psi_2}{A_1 \cos \psi_1 + A_2 \cos \psi_2} \quad (6) \quad 95$$

Now, since the phase angle constants in the foregoing equations are functions of the transmitting antennae and the transmitting media, which are assumed to be the same for both transmission east and west, it is evident that the expressions $\cos(\theta_2 - \theta_1)$ and $\cos(\psi_2 - \psi_1)$ in Equations (3) and (4) will be equal to each other, and hence the terms under the radicals in said equations are equal. It is also evident that I_E plus I_w add up to zero whenever

100

105

$$\frac{4\pi x}{\lambda} + \psi_3 - \theta_3 = \pm n\pi \text{ radians} \quad (7)$$

where *n* is any odd number. It follows, therefore, that at points approximately midway between the broadcasting stations a change in θ_3 or ψ_3 will cause the total received current to vary or even to disappear.

Varying field strength may be eliminated by keeping the oscillators at the two transmitting stations in perfect synchronism. If, instead of using oscillators, the carrier wave is provided at each station by means of harmonic generators of radio frequency driven

110

115

120

or controlled by the same fundamental controlling current (preferably of voice frequency) transmitted over a telephone line between the stations, the phase relation between the two radio currents will be constant, provided the phase relation between the fun-

125

130

damental controlling currents at the sending and receiving ends of the telephone line is constant.

Fig. 4 illustrates schematically apparatus for maintaining the phase relation of the currents at the sending and receiving ends of the telephone line constant. In this figure, RT and RT' represent symbolically any known type of radio transmitter including means for deriving a carrier wave by harmonic generation from a fundamental wave generated by a source S. The fundamental controlling wave from the source S is transmitted from the radio station at which the transmitter RT is located over a line L₁ to the station at which the radio transmitter RT' is located. In order that the controlling current I₂ arriving at the station RT' will always have a constant phase relation with respect to the controlling current I₁ leaving the originating or sending station at which the source S is located, a return line L₂ is provided. Changes in phase due to temperature variations which affect the resistance and capacity of the cable, which includes the two telephone lines L₁ and L₂, may be compensated for by variable phase controlling networks PN₁ and PN₂. These phase shifting networks may be moved together so that when a phase change of δ degrees occurs in the current I₃ returning to the originating station, each network causes a compensating shift of $\frac{\delta}{2}$ degrees. When conditions are normal, the adjustment of the lines L₁ and L₂ is such that the returning current I₃ is 90° out of phase with the current I₁ leaving the source S. In order to maintain this phase condition with respect to the currents I₁ and I₃, and in order to automatically produce the necessary compensating adjustment of the networks PN₁ and PN₂, a push-pull detector circuit, comprising detector tubes 4 and 5, is provided, and the input circuits of these tubes are so arranged that the current I₁ from the source S is applied serially to the grids of the two tubes through the transformer 1, while the returning current I₃ is applied to the grids in parallel through the transformer 3. Resistances are connected across the plate circuits of the two tubes, and the polar relay PR, for operating the control mechanism (see Fig. 6), is connected across the terminals *xy*.

The operation of the push-pull detector may be understood by reference to Fig. 5. When the voltage E₁ changes from its 90° relation with E₃ by an amount δ , the voltage E₄ on the grid of one of the tubes is increased, while the voltage E₅ on the grid of the other tube is decreased. Consequently, the rectified current in one tube is increased while that in the other tube is decreased. Accordingly, when matched tubes are employed there will result a positive or negative potential between the points *x* and *y*, depending upon

the sign of the phase variation δ . When the normal 90° relation exists between the currents I₁ and I₃, there will be no potential drop between the points *x* and *y*, and the armature of the polar relay PR will be in its neutral position. If the phase varies in one direction, however, the armature of the polar relay is shifted to, say, its upper position, thereby energizing the relay 7 and causing the motor M to be driven in one direction. If the phase variation is in the opposite direction, however, the armature of the polar relay will be shifted to its lower contact, thereby energizing relay 8 to drive the motor M in the opposite direction. The motor M may be geared by means of any suitable mechanism to simultaneously vary the phase adjusting networks PN₁ and PN₂.

The control mechanism illustrated in Fig. 6 is merely a conventional representation of mechanism capable of carrying out the desired function. It will be understood that any other suitable mechanism well known in the art may be employed for this purpose. Likewise, the variable phase shifting networks PN₁ and PN₂, which are merely symbolically indicated, will be understood to be any one of the many types of phase shifting mechanism known in the art.

It will be obvious that the general principles herein disclosed may be embodied in many other organizations widely different from those illustrated without departing from the spirit of the invention as defined in the following claims.

What is claimed is:

1. In a system in which alternating current from a source located at one station is supplied to a translating device located at a distant station which is connected to the first station by two transmission paths, each having individual phase controlling elements, the method of maintaining a constant phase relation between the current at the two stations which consists in transmitting the alternating current from the source at the first station to the distant station over one path, transmitting the current incoming at the distant station back to the first station over the second path, observing any variation in the normal phase difference between the leaving and arriving currents at said first station, and adjusting the phase controlling elements individual to the two paths so that each element compensates for that portion of the observed variation which is due to the phase shift of its path.

2. In a signaling system, an alternating current source located at one station, a translating device supplied with current from said source and located at a distant station, a transmission path over which alternating current from said source is transmitted to said distant station, a path over which current incoming at said distant station is transmitted

- back to said first station, means at said first station for indicating variations in the normal phase difference between the leaving and arriving currents thereat, and adjustable phase controlling networks in each of said paths, each network being adjustable to compensate for that portion of the indicated variation in phase difference which is due to the phase shift of its path. 5
3. In a signaling system, an alternating current source located at one station, a translating device supplied with current from said source and located at a distant station, a transmission path over which alternating current from said source is transmitted to said distant station, a path over which current incoming at said distant station is transmitted back to said first station, controlling means at said first station for indicating variations in the normal phase difference between the leaving and arriving currents thereat, adjustable phase controlling networks in each of said paths, and connections between said networks and said controlling means whereby each network will be adjusted to compensate for that portion of the indicated variation which is due to the phase shift of its path. 20
4. In a signaling system, an alternating current source located at one station, a translating device supplied with current from said source and located at a distant station, a transmission path over which alternating current from said source is transmitted to said distant station, a path over which current incoming at said distant station is transmitted back to said first station, said paths being normally so adjusted that a phase difference of 90° will exist between the leaving and arriving currents at said first station, controlling means unresponsive to said leaving and arriving currents when a phase difference of 90° exists between them, adjustable phase controlling networks in each of said paths, and connections from said controlling means, to said networks whereby said controlling means will operate when any variation from said 90° phase difference occurs to adjust each network to compensate for that portion of the variation which is due to the phase shift of its path. 45
5. In a signaling system, an alternating current source located at one station, a translating device supplied with current from said source and located at a distant station, a transmission path over which alternating current from said source is transmitted to said distant station, a path over which current incoming at said distant station is transmitted back to said first station, said paths being normally so adjusted that a phase difference of 90° will exist between the leaving and arriving currents at said first station, a push-pull detector circuit and a polar relay controlled thereby, connections whereby said 60
- leaving and arriving currents at said first station may be applied to said push-pull circuit in such relation that when a 90° phase shift exists the armature of said relay will be in a neutral position, adjustable phase controlling networks in each of said paths, and mechanism controlled by said polar relay to adjust each of said networks to compensate for that portion of any variation from the 90° phase difference normally existing between said leaving and arriving currents which is due to the phase shift of the path in which the network is located. 70
